(57) **CLAIM**

The ornamental design for a board peripheral for video game, as shown and described.

DESCRIPTION

FIG. 1 is a perspective view of a board peripheral for video game, showing our new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a left side elevational view thereof, the right side elevational view being a mirror image thereof.

The broken lines depict environment of the board peripheral for video game and form no part of the claimed design.
